UNITED STATES PATENT OFFICE.

CHARLES A. BAZINO, OF NORTH BENNINGTON, VERMONT.

BLOWER FOR KNITTING-MACHINES.

1,141,034.

Specification of Letters Patent. Patented May 25, 1915.

Application filed April 18, 1914. Serial No. 832,909.

To all whom it may concern:

Be it known that I, CHARLES A. BAZINO, a citizen of the United States, residing at North Bennington, in the county of Bennington and State of Vermont, have invented certain new and useful Improvements in Blowers for Knitting-Machines, of which the following is a specification.

This invention relates to improvements in textile machinery and more particularly to an attachment for a knitting machine to prevent the stopping of the machine due to the gathering of lint or fine particles of yarn in the various parts of the machine.

15 The primary object of this invention is the provision of a blower attachment for knitting machines which has egressing openings adjacent the quarter-saver of a knitting machine to prevent the lint or fine particles of 20 yarn from clogging or obstructing the efficient operation of the quarter-saver.

With the foregoing and other objects in view this invention consists in such novel features of construction, combination and 25 arrangement of parts as will be hereinafter more fully described, illustrated in the accompanying drawings and claimed.

In describing the invention in detail reference will be had to the accompanying 30 drawings wherein like characters of reference designate like or corresponding parts throughout the several views, and in which:—

Figure 1 is a plan view of a fragment of 35 a knitting machine showing the improved blower and connections attached thereto. Fig. 2 is a side elevation of Fig. 1, and Fig. 3 is a cross sectional view through the egressing portion of the pipe which is disposed 40 about the quarter-saver of the knitting machine.

Referring more particularly to the drawings, 1 designates a fragment of a knitting machine, of any ordinary type of construction now employed for the purpose of knitting various articles, and which has a quarter-saver 2 attached thereto. The quarter-saver 2 is of the usual type of construction employed in connection with knitting machines and it has a plurality of upstanding pins 3, which pins form a part of the mechanism for automatically stopping the feeding of the yarn when the same becomes broken, and these pins oftentimes become 55 clogged with lint or fine particles of yarn

rendering the operation of the quarter-saver imperfect. To prevent the clogging of the quarter-saver by lint a pipe 4 is mounted circumferentially about the outer edge of the quarter-saver and the pipe 4 is provided 60 with a plurality of circumferentially spaced openings 5, which openings are provided for permitting the egress of air from the pipe 4 and properly guiding it to blow lint or fine particles of yarn from the quarter-saver. 65

The pipe 4 is connected through the medium of pipes 6 to the outlet of a fan or blower 7 which fan or blower is disposed at any convenient location within the knitting mill and which is operated by a belt 8 passing over the pulleys 9 and 10. The pulley 10 is rotated by the rotation of a line shaft 11, which shaft is in turn rotated by any suitable prime mover (not shown). A valve 12 is interposed in the series of pipings 6 and 70 it controls the flow of air through the pipes 6 and 4.

In the installation of the device hereinbefore described, the pipes 6 may be positioned beneath the floor of the knitting mill and 80 connected to any desirable number of circular pipes 4, which pipes may be disposed about the quarter-savers of the various knitting machines, and when the machinery is set in motion, the rotation of a line shaft 11 85 will rotate the pulley 10 and consequently the fan or blower 7, forcing a volume of air through the pipe 6 and out through the circumferentially spaced openings 5 which are 90 formed on the inner sides of the pipes 4 on to the quarter-savers as heretofore described.

From the foregoing description taken in connection with the accompanying drawings the advantages of the construction and of the method of operation of the improved 95 blower attachment will be readily apparent to those skilled in the art to which this invention appertains and, while in the foregoing description, the principle of the operation of this invention has been described together with various features of construction, it is to be understood that certain minor 100 features of construction, combination and arrangement of parts may be altered to suit practical conditions provided such alterations are comprehended within the scope of what is claimed.

What is claimed is:—

1. In combination with the presser wheel 110 of a quarter-saver, of a blower and a nozzle

connected to the blower to direct air from the blower on said presser wheel preventing the accumulation of lint thereon.

2. In combination with the presser wheel of a quarter-saver having a plurality of pins, of a blower, and a circular pipe surrounding the pins and having communication with the blower, said pipe having openings adapted

to direct air from the blower on to the pins to prevent the accumulation of lint thereon. 10

In testimony whereof I affix my signature in presence of two witnesses.

CHARLES A. BAZINO.
